UNITED STATES PATENT OFFICE.

GEORGE WILLIAM MOHR, OF JERSEY CITY, NEW JERSEY.

HORSE-OVERSHOE.

1,296,203.

Patented Mar. 4, 1919.

Application filed November 22, 1918. Serial No. 263,655.

To all whom it may concern:

Be it known that I, GEORGE W. MOHR, a citizen of the United States, and resident of Jersey City, in the county of Hudson and State of New Jersey, have invented a new and useful Improvement in Horse-Overshoes, of which the following is a specification.

The object of the invention is to provide a convenient and serviceable overshoe for horses adapted to be put on over a smooth or worn shoe to enable the horse to be effectively rough-shod whenever desired in slippery weather, without reshoeing. The invention comprises certain novel features and combinations thereof, as will presently appear, contributing to this end.

In the accompanying drawings forming a part hereof:

20 Figure 1 is a side elevation of the overshoe applied to a hoof shod with an ordinary shoe in which the toe and heel calks may be understood as having worn down;

25 Fig. 2 is a vertical longitudinal section through the same, the front calk of the nailed shoe being shown less worn, and front calks with lower heads being used on the overshoe;

30 Fig. 3 is a similar view of a modification, illustrating removable calks with still lower heads;

Fig. 4 is a front elevation;

35 Figs. 5, 5^a and 5^b are elevations of some different calks which may be employed;

Fig. 6 is a plan view of the form shown in Figs. 1 and 2;

Fig. 7 is a vertical cross-section on the line 7—7 of Fig. 6; and

Fig. 8 is a plan view of the form shown 40 in Fig. 3.

The hoof is designated *a*, and an ordinary shoe thereon *b*.

The overshoe comprises a sole plate 1, which is preferably solid as shown in Figs. 1, 45 2 and 6, but may be open. An open plate 1^a is shown in Fig. 8. In either event the plate is so formed as to extend beneath the nailed shoe from toe to the heel thereof inclusive, and is integral, as distinguished from one 50 made of jointed sections. The top part of the plate is cut away across the front, forming

ing a toe recess 2, and at the rear corners heel recesses 3 are provided. These recesses will accommodate what may remain of the toe and heel calks of the shoe *b*.

55

Two or more vertical calk openings 4 are formed through the bottom wall of the toe recess 2 and similar openings are formed through the bottom walls of the heel recesses 3. Into these openings removable calks 5 are

60

inserted from the top, so that their pointed ends project below the plate. The holes and the upper parts of the shanks of the calks are preferably screw-threaded, but this is not essential, though desirable to avoid looseness.

65

The shoe *b* is shown as smooth and flat on the bottom in Fig. 1, but in practice the original toe and heel calks will naturally wear unevenly. In order to allow for this condition the calks 5 are provided with dif-

70

ferent heights of head as shown, to be used interchangeably. So situated, the calks cannot drop out, because of the portions of the plate beneath the heads, nor work up, be-

75

cause of the toe and heel of the shoe above the heads. The heads of the calks lie within the recesses below the surface of the plate on which the nailed shoe rests, and as stated the recesses also accommodate what remains of

80

the calks of the nailed shoe, the removable calks underlying the old calks. Inserting the calks down from the top, instead of up from the bottom, as is the ordinary practice with removable calks, possesses the double

85

advantage that the calks cannot wear loose and drop out, and that when a new calk is to be put in it is first entered into a part of the hole which has been protected from wear, and hence it can be readily started and then forced, if necessary, down into place. Ex-

90

perience with calks screwed up from below has showed me that replacement of such a calk is likely to be difficult, or impossible without re-tapping, because of the bottom of

95

the threaded hole having become worn or the thread distorted. As far as I am aware I am the first to provide an overshoe, applicable beneath a nailed shoe, having, or capable of having, calks inserted down from above, these calks being located at the true toe and heel regions. The location of the calks is important, because it is at these regions

100

where the horse naturally obtains its grip on icy surfaces, and because if calks are placed at the intermediate region, so as to shorten the base, the hoof will rock, while a multiplicity of calks distributed from front to rear renders the grip less effective.

Clips 6 projecting upward from the side front portions of the sole-plate, and clips 7 similarly projecting from the rear side portions, embrace the nailed shoe and preferably also the lower part of the hoof and constitute rigid abutments preventing the plate from slipping rearward or sidewise relatively to the hoof and nailed shoe; the clips 7, being rearward of the greatest width of the average shoe, also prevent forward displacement. At the back there may also be a raised rib or stop 8, which is useful more particularly to keep the plate from slipping forward on broad, short shoes and shoes with rubber heels, this back stop being relatively low and adapted to coöperate with the heel of the nailed shoe without bearing against the soft back part of the hoof.

The advantage of the solid over the open sole-plate is that it will exclude snow and mud; and in order to prevent such material entering at the rear a transverse packing strip 9 of felt or other suitable material is shown upon the top of the plate near the rear, and slightly in front of the heel recesses 3, terminating at its ends inwardly of the sides of the sole plate, and of a length to extend between the side members of the shoe and to fill the space between the hoof and plate, this strip being secured to the plate in any suitable manner.

A common anchorage member or plate 10 is curved to fit the front upper part of the hoof, as shown in Fig. 1. A tension member 11, consisting preferably of a metal strap, is secured by a hinge connection or otherwise to the clip 7 at the inner side of the sole-plate and thence extends upward and forward over the hoof to a point of attachment 12 on the adjacent lateral portion of the anchorage plate 10. The said point of attachment is desirably in the nature of a permanent, flexible connection, and may be a hinge, as shown. Another tension member 11^a is united with the other rear clip 7, and passes upward and forward like the member 11, its upper end being preferably formed with an arrow or T-head 13, constituting a member of a separable connection coöperating with a pair of lugs 14 on the corresponding lateral portion of the anchorage plate. A turnbuckle 15 in the member 11^a enables this member to be tightened and loosened when putting on and taking off the overshoe. By undercutting the abutting surfaces of the lugs and head as indicated at 16 in Fig. 4, disengagement is permitted only after a certain amount of loosening at

the turnbuckle, so that accidental separation is guarded against. The tightening means is located at the outer side of the hoof in order that there may be no danger of injury to the horse by striking the other leg, and for the same reason the member 11, at the inner side, or at least its lower portion, and its connection with the sole-plate, are made so as to lie close to the hoof.

A pair of front tension members 17 are connected with the clips 6, at what may be termed the forward corner regions of the sole-plate, and extend upward and rearward in converging relation upon the hoof, being preferably united with each other in V-form and provided with a common central extension 18, containing a turnbuckle 19 and a head 20, the latter coöperating with a pair of lugs 21 on the central lower part of the anchorage plate, after the manner of the head and lugs 13 and 14 already described. The clips 6 may be twisted at the top, in order that hinge connections 22 may be provided, the axes of which will be in alinement.

It will be understood, however, that I do not limit myself to the precise form of the fastening means.

The overshoe of Figs. 3 and 8 is designed for use with shoes in which the usual heel portions are omitted and replaced with a transverse rubber heel. In such cases, the sole-plate 1^a, instead of having the corner heel recesses 3 of the other form, is recessed entirely across the top and rear, to receive a plate section 23, which is held in place by screws 24 or otherwise, and prevents the rear calks 5 working upward into the rubber heel.

It will be apparent that the overshoe can be quickly and readily applied and removed, and when tightened is secure against displacement. The calks can be replaced as often as may be necessary to insure against slipping, and may be of various styles. It may be noted that the calks are readily removable and replaceable, that is to say by hand or with ordinary implements such as a screw-driver or wrench, as distinguished from operations requiring a mechanic or horseshoer or special tools and appliances. The recesses and openings in which they are received are entirely accessible when the overshoe is off the hoof, and when in use the removable calks are held between the sole-plate and the nailed shoe, except in the special case of the heel calks of Figs. 3 and 8, where their heads are covered by an additional plate section, which, however, is removable in the same convenient manner as the calks themselves, that is to say by unscrewing.

What I claim as new is:

1. A horse overshoe having a sole-plate formed to extend beneath a nailed shoe from

- 5 toe to heel thereof inclusive and provided with means for holding it in place, said plate having recesses in its upper side at the toe and heel with openings through the bottoms of said recesses, and removable headed calks inserted downward through said openings with their heads below the surface of the plate on which the nailed shoe rests, whereby the removable calks and the worn 10 calk part of the nailed shoe are both accommodated one below the other, the removable calks being prevented from coming out.
- 15 2. A horse overshoe having a sole-plate formed to extend beneath a nailed shoe from toe to heel thereof inclusive and provided with means for holding it in place, said plate having recesses in its upper side at the toe and heel with openings through the bottoms of said recesses, in combination with removable and interchangeable calks having shanks adapted to be inserted downward through said openings and heads of different heights to underlie the worn calk part of the nailed shoe.
- 20 25 3. A horse overshoe comprising an integral sole-plate with means for holding it in place beneath a nailed shoe, said plate having a recess in its upper side at the extreme toe region adapted to receive the worn toe calk of the nailed shoe, and openings through the bottom of said recess, removable calks inserted downward through said openings with heads adapted to be accommodated beneath the worn toe calk of the shoe, and other removable headed calks inserted 30 35 downward through the heel portions of the plate.
- 40 4. A horse overshoe comprising a sole-plate with means for holding it in place beneath a nailed shoe, said plate having recesses in its upper side at the extreme toe and heel regions adapted to receive the worn toe and heel calks of a nailed shoe, and openings through the bottoms of said recesses, and removable headed calks inserted 45 50 downward through said openings to be held against dropping out by the portions of the plate beneath the heads and against upward movement by the shoe.
- 55 5. A horse overshoe, comprising a sole-plate provided with means for holding it beneath a nailed shoe, said sole-plate having accessible recesses in its upper side with openings through the bottoms of said recesses, and headed calks having their shanks extending downward through said openings and their heads accommodated in said recesses below the surface of the plate upon which the nailed shoe rests.
- 60 6. In a horse overshoe, the combination of a sole-plate adapted to be held beneath a nailed shoe, said plate having an accessible recess in its upper side and a screw-threaded opening through the bottom of said recess, a removable calk having a screw-threaded shank extending downward through said opening and a head accommodated in said recess.
- 65 7. A horse overshoe comprising an integral sole-plate adapted to extend beneath a nailed shoe from the toe to the heel thereof inclusive and having recesses in its top positioned to receive the worn toe and heel calks of the shoe, removable calks in said recessed portions of the plate, clips projecting up from the side front and side rear portions of the plate to prevent horizontal displacement, and fastening means connected with said clips and adapted to pass over the hoof.
- 70 75 8. A horse overshoe comprising an integral sole-plate adapted to extend beneath a nailed shoe from the toe to the heel thereof inclusive and having recesses in its top positioned to receive the worn toe and heel calks of the shoe, removable calks in said recessed portions of the plate, clips projecting up from the side front and side rear portions of the plate to prevent horizontal displacement, an additional low back-stop on the plate adapted to coöperate with the heel of 80 85 the nailed shoe without bearing upon the soft part of the hoof, and fastening means connected with said clips and adapted to pass over the hoof.
- 90 9. A horse overshoe comprising a solid calk-bearing sole-plate, a transverse packing-strip on top of said plate adjacent the rear and terminating at its ends inwardly of the sides of the plate adapted to come under the hoof to prevent entrance of material between the hoof and the plate, and means for holding said plate in place.
- 95 10. In a horse overshoe, the combination with a sole-plate, of fastening means comprising a common anchorage member 100 105 adapted to be applied to the front of the hoof, and tension members connected with the forward and rearward portions of the sole-plate and provided with turnbuckles and means of separable connection upon said anchorage member.
- 110 11. In a horse overshoe, the combination with a sole-plate, of fastening means comprising a common anchorage member adapted to be applied to the front of the hoof and having undercut lugs, and tension members connected with the forward and rearward portions of the sole-plate and having tightening means and heads adapted to hook with said undercut lugs.
- 115 12. In a horse overshoe, the combination with a sole-plate, of fastening means comprising a common anchorage member adapted to be applied to the front of the hoof, and tension members connected with the forward and rearward portions of the sole-plate and having means of separable connection upon said anchorage member, the
- 120 125

forward members being united in V-form and having a common member provided with tightening means extending upward to the anchorage member.

5 13. A horse overshoe comprising an integral sole-plate with means for holding it in place beneath a nailed shoe, said plate having a recess in its upper side at the ex-

treme toe region adapted to receive the worn toe calk of the nailed shoe, and openings 10 through the bottom of said recess, removable calks inserted downward through said openings with heads adapted to be accommodated beneath the worn toe calk of the shoe.

GEORGE WILLIAM MOHR.
